(57) **CLAIM**

The ornamental design for a can end sealant gun bracket, as shown.

DESCRIPTION

FIG. 1 is a perspective view of the can end sealant gun bracket.

FIG. 2 is a front view of the can end sealant gun bracket.

FIG. 3 is a back view of the can end sealant gun bracket.

FIG. 4 is a top view of the can end sealant gun bracket.

FIG. 5 is a bottom view of the can end sealant gun bracket.

FIG. 6 is a first side view of the can end sealant gun bracket; and,

FIG. 7 is a second side view of the can end sealant gun bracket.

The broken lines in the figures depict portions of the can end sealant gun bracket that form no part of the claimed design.
